UNITED STATES PATENT OFFICE

JOHN D. PEDERSEN, OF SPRINGFIELD, MASSACHUSETTS

CARTRIDGE CLIP

Application filed January 14, 1928. Serial No. 246,827.

This invention relates to a cartridge clip and has for its object an improved form of clip for holding a stack of cartridges en bloc in tight compact form and adapted to accompany the cartridges into the magazine of a gun. A type of gun for which the present clip is particularly adapted is shown and described in my companion application Serial No. 197,718, filed June 9, 1927.

10 The clip of this invention is of the expendable type,—that is, cheap enough in construction so that it may be thrown away after a single use if desired; and is designed to serve several purposes,—namely, as a holder for 15 the cartridges outside of the gun, as a retainer for facilitating the charging of the cartridges by hand into the magazine, and as a guide in the magazine to direct the cartridges into proper position for loading. A 20 modified form of the clip as shown will also serve to lubricate the cartridges preparatory to the loading thereof. In the present embodiment of the invention, I have secured these objects by the employment of a single 25 integral piece of sheet metal or stamping, bent into suitable configuration and possessing the requisite degree of strength, springiness and lightness to successfully accomplish the purposes for which it is designed.

30 The feature in such a clip of being charged with the cartridges into the magazine chamber of the gun instead of having the cartridges stripped from the clip for charging, materially increases the rapidity of firing possible in 35 automatic guns. For the most advantageous employment of such a clip, the gun should be provided with suitable means for discharging the clip automatically upon the exhaustion of its cartridges so that the gun may be ready 40 for rapid recharging. Suitable mechanism of this character for cooperation with the clip is shown in my companion application above referred to.

An important feature of novelty in the 45 present clip is that it is designed to hold a stack of cartridges in double row and to impart a confining pressure upon said stack in such a manner as will hold the cartridges securely and firmly in fixed relation, i. e., in en bloc form under all usual conditions of han-

dling and ready for charging into a magazine. The confining pressure thus afforded by the clip for holding the stack involves the balancing of both a vertical and lateral pressure upon the stack so as to maintain a uniform 55 double-row arrangement of the stack. Preferably, when the clip is charged into a magazine chamber, the lateral pressure of the clip upon the stack is relieved by suitable coacting devices in the gun whereby feeding mechanism for the cartridges may operate on a stack with less resistance to overcome.

Further advantages pertaining to details of construction will appear in the description which follows. The objects of the invention are obtained by means of the construction hereinafter described, and the scope of the invention will be pointed out in the appended claims. Referring to the drawings, which show a preferred embodiment of the invention:

Fig. 1 is a partial view in longitudinal section of a gun with which the clip of this invention is adapted to cooperate and showing the clip with its cartridges in position after 75 being charged into the magazine chamber of said gun;

Fig. 2 is a partial view in plan of said gun showing the magazine chamber;

Fig. 3 is a rear end view of the cartridge 80 clip with the cartridges en bloc therein;

Fig. 4 is a front view of the same;

Fig. 5 is a top view of the same;

Fig. 6 is a horizontal section along line A—A of Fig. 3 showing the action of the 85 cartridge retaining ribs;

Fig. 7 is a fragmentary vertical section somewhat enlarged along line B—B of Fig. 5 to show the upper termination of the cartridge retaining ribs;

Fig. 8 is a view of the upper end of a modified form of clip containing lubricating pockets.

As shown in Fig. 1, the cartridges C held 95 by the clip are of the usual tapered form and when closely packed in the clip are arranged to lie with the uppermost cartridges in substantially horizontal position ready for loading and with the underneath cartridges in 100

positions of progressively greater inclination as they approach the bottom.

The clip is preferably a one piece integral member of thin spring metal or stamping comprising a rigid back 145 and two spring tensioned sides 146, 147 cut out in places for lightness and suitably stiffened by upset depressions or ribs. It should be noted that the depressed ribs 148 on the back are inclined to the horizontal and to the direction of feeding travel for the cartridges so that the base of the cartridges will not catch or foul therein when being fed upwardly into loading position. The clip itself carries no feeding means as is the case with box-like detachable magazines; but suitable feeding means are provided on the gun for coacting with the present clip. As shown in Fig. 1, a spring actuated follower 159 is mounted on the gun for a travel through the clip in feeding the cartridges upwardly.

The back 145 and sides 146, 147 of the clip form in effect a receptacle for the cartridges open at the front, top and bottom. The sides 146, 147 tend to converge from the back 145 toward the front so as to impart lateral spring pressure against the stack of cartridges. At the bottom of the clip, the sides 146 and 147 have inwardly turned portions or prongs 149, 150 respectively which are spring tensioned to press upwardly against the lowermost cartridges of a full stack to furnish a vertical pressure in holding the same securely and compactly. The tapered form of the cartridges enables the lateral and vertical pressure of the clip to compress the stack together into a solid unitary mass.

Adjacent the rear edge of each side 146, 147 of the clip and projecting inwardly are ribs 151 and 151' (see Figs. 6 and 7) which serve as cartridge retaining ribs and in conjunction with the wedging action of the tapered cartridges in the stack act to hold the cartridges from slipping out of the clip while being handled outside of the gun and also to prevent any forward throw of the cartridges under the recoil impulse of firing when in the magazine. These ribs extend from the bottom of the clip to a short distance from the top and the rib 151 on one side engages in front of the extracting rim of one row of cartridges while the rib 151' on the other side engages similarly the other row of cartridges, as shown in Fig. 6. The ribs 151, 151' do not extend to the top of the clip and thereby leave the top cartridge free for loading, as shown in Fig. 7. These ribs do not extend vertically parallel with the back 145 of the clip but diverge therefrom slightly toward the bottom to allow for the increased inclination of the cartridges.

At the top of the clip, each side is formed with inwardly turned portions 152, 153 which are relatively stiff and serve to guide the uppermost cartridge as it is loaded into the

gun chamber. The cut out portion 154 of the back allows the travel of the loading member or bolt 23 of the gun therethrough in loading the cartridges. It will be observed that the arrangement of the cartridges in the clip is such that the bolt will engage the topmost cartridge first from one row and then from the other in loading the same.

On the back of the clip is formed the outwardly offset locking nib 135 which is engageable by a suitable clip latch 132 for holding the clip in the magazine chamber. The clip latch 132 and its attendant operating mechanism forms no part of the present invention but it will be understood that said latch automatically engages the clip when charged into the magazine and at the proper time is operated to release the clip for its discharge. The nib 135 is located off center or at one side of the center line of the back, and a clearance groove or channel 155 is formed in the rear wall of the magazine chamber (see Fig. 2) to receive this nib 135 when the clip is charged into the magazine. If any attempt is made to insert the clip upside down, the offset position of the nib will prevent its introduction.

Each side of the clip at its front edge is formed with an inwardly depressed bump 156, 157 which, when the clip is introduced into the magazine chamber, will engage behind ledges 158, 158' provided on each side wall of the chamber, and thereby cause a spreading apart of the clip sides. In this way, the stack of cartridges, when in the chamber, is relieved from the lateral tension of the clip whereby the follower may feed the cartridges more easily.

In some cases it may not be necessary for the bumps 156, 157 of the clip in engaging the ledges 158, 158' of the gun to actually spread the sides of the clip apart, as it may be satisfactory for the ledges 158, 158' to merely prevent the sides of the clip from moving any closer together after the removal of one or more cartridges from the stack. When the clip is full with its double row of cartridges, the contracting pressure of its sides can only hold the stack snugly as a unit; but with less than a full stack, the pressure of the clip sides may tend to throw the depleted rows out of their proper alignment (viz, a tendency toward making one row out of the two rows) and thus disturb the proper feeding. For this reason, it is very desirable, with a pressure clip of this character holding a double row, to prevent the clip sides from contracting beyond their normal position with a full stack, during the feeding operation while in the gun.

The modified form of clip shown in Fig. 8 is in all respects similar to that heretofore described except that the upper inwardly curved portions 152^a and 153^a of the sides are

provided with lubricating means for the cartridge. In this embodiment, said lubricating means are constituted by depressed pockets 152^b and 153^b which serve to hold a thick lubricant such as cosmoline. If desirable, an oiled wick may be secured in said pockets, the object in either case being to dab a small portion of lubricant upon each cartridge as it travels past said pockets in the loading operation. It is an advantage to have well lubricated cartridges for use in automatic guns and by the means described this lubrication is effected in a simple and effective manner.

From the foregoing description, it will be appreciated that an efficient and inexpensive clip is provided which will have the advantage of expendability and light weight possessed by the stripping type of clip as well as the advantage of being both a holder and guide possessed by the detachable magazine box heretofore commonly employed in automatic guns. It will be understood that the invention is not to be confined to the preferred embodiment thereof herein described and shown but that various changes may be made therein without departing from the scope and spirit of the invention as claimed.

What I claim is:

1. A cartridge clip for holding a stack of cartridges in a double row comprising a back and two sides forming a receptacle open at the front, top and bottom, the sides of said clip arranged to impart a lateral pressure on said stack.

2. A cartridge clip for holding a stack of cartridges in a double row comprising a back and two sides, forming a receptacle open at the front, top and bottom, the sides of said clip arranged to impart a lateral pressure on said stack, and having inwardly extending portions at the top and bottom of said clip for confining said stack in said clip.

3. A cartridge clip for holding a stack of cartridges in a double row comprising a back and two sides, forming a receptacle open at the front, top and bottom, the sides of said clip arranged to impart a lateral pressure on said stack, and having inwardly extending portions at the top and bottom of said clip for confining said stack in said clip, the inwardly extending bottom portions of said sides arranged to impart a vertical pressure on a full stack confined in said clip.

4. A cartridge clip for holding a stack of cartridges in a double row comprising a back and two sides forming a receptacle open at the front, top and bottom, and lubricating means for said cartridges comprising lubricant retaining pockets formed in the sides of said clip.

5. A cartridge clip for holding a stack of cartridges in a double row in staggered mutually engaging relation and comprising a back and two sides, a cartridge retaining rib on one side of said clip for engaging in front of

the extracting rim of one row of cartridges in said stack, and a cartridge retaining rib on the other side of said clip for engaging in front of the extracting rim of the other row of cartridges in said stack.

6. A cartridge clip for holding a stack of cartridges in a double row comprising a back and two sides, a cartridge retaining rib on one side of said clip for engaging in front of the extracting rim of one row of cartridges in said stack, and a cartridge retaining rib on the other side of said clip for engaging in front of the extracting rim of the other row of cartridges in said stack, said retaining ribs terminating below the top of said clip so as not to engage the cartridge at the top of said clip which is in position for being loaded from the clip.

7. A cartridge clip for holding a stack of cartridges in a double row, comprising a back and two sides forming a receptacle open at the front, top and bottom, said sides arranged to impart a lateral pressure on said stack, a cartridge retaining rib on one side of said clip for engaging in front of the extracting rim of one row of cartridges in said stack, and a cartridge retaining rib on the other side of said clip for engaging in front of the extracting rim of the other row of cartridges in said stack.

8. A cartridge clip for holding a stack of cartridges in a double row comprising a one piece integral member having a back and two spring metal sides converging toward an open front so as to impart a lateral pressure on said stack.

9. A cartridge clip for holding a stack of cartridges in a double row comprising a one piece integral member having a back and two spring metal sides converging toward an open front so as to impart a lateral pressure on said stack, said sides having inwardly turned relatively rigid portions at the top of said clip and inwardly turned spring yielding portions at the bottom of said clip for confining said stack in said clip.

10. A cartridge clip for holding a stack of cartridges in a double row comprising a one piece integral member having a back and two spring metal sides converging toward an open front so as to impart a lateral pressure on said stack, a cartridge retaining rib on one side of said clip for engaging in front of the extracting rim of one row of cartridges, and a cartridge retaining rib on the other side of said clip for engaging in front of the extracting rim of the other row of cartridges in said stack.

11. A cartridge clip for holding a stack of cartridges in a double row comprising a one piece integral member having a back and two spring metal sides converging toward an open front so as to impart a lateral pressure on said stack, the back of said clip being stiffened transversely by offset depressions

extending diagonally across said back, said sides having inwardly turned relatively rigid portions at the top of said clip and inwardly turned spring yielding portions at the bottom of said clip for confining said stack in said clip.

12. A cartridge clip for holding a stack of cartridges in a double row comprising a one piece integral member having a back and two 10 spring metal sides converging toward an open front so as to impart a lateral pressure on said stack, the back of said clip being stiffened transversely by offset depressions extending diagonally across said back, said 15 sides having inwardly turned relatively rigid portions at the top of said clip and inwardly turned spring yielding portions at the bottom of said clip for confining said stack in said clip, a cartridge retaining rib on one side of 20 said clip for engaging in front of the extracting rim of one row of cartridges, and a cartridge retaining rib on the other side of said 25 clip for engaging in front of the extracting rim of the other row of cartridges in said stack.

13. A cartridge clip for holding a stack of cartridges comprising a back and two sides forming a receptacle open at the front, top and bottom, the back of said clip being stiffened transversely by offset depressions extending diagonally across said back.

14. A cartridge clip for holding a stack of cartridges and adapted to be contained with said cartridges in the magazine chamber of a 35 gun, said clip comprising a back and two sides forming a receptacle open at the front, top and bottom, the sides of said clip arranged to impart a lateral pressure on said stack, and provided with means for engagement by elements of the gun to spread the 40 sides of said clip to relieve the lateral pressure on said stack when in said chamber.

15. A cartridge clip for holding a stack of cartridges, comprising a back and two sides 45 forming a receptacle open at the front, top and bottom, the sides of said clip arranged to impart a lateral pressure on said stack, a latching nib on the back of said clip in off center position in combination with the 50 magazine chamber of a gun adapted to contain said clip of cartridges, and having a receiving channel for said latching nib arranged to permit the introduction of said clip into said magazine only in its right side up position.

16. A cartridge clip for holding a stack of cartridges in a double row in staggered mutually engaging relation and adapted to be contained with said cartridges in the magazine chamber of a gun, said clip comprising 60 stack embracing side portions arranged to impart a lateral pressure on the stack and provided with means for engagement by elements of the gun when inserted therein so as 65 to prevent the contraction of the sides of the

clip when any of the cartridges are removed from the stack.

17. A cartridge clip for holding a stack of cartridges in a double row in staggered mutually engaging relation and adapted to be contained with said cartridges in the magazine chamber of a gun, said clip comprising a back and two sides forming a receptacle open at the front, top and bottom, the sides of said clip extending over the sides of the stack and arranged to impart a lateral pressure on the stack and provided with means for engagement by elements of the gun when inserted therein so as to prevent the contraction of the sides of the clip when any of the cartridges 70 75 80 are removed from the stack.

18. A cartridge clip for holding a stack of cartridges in a double row in staggered mutually engaging relation and adapted to be contained with said cartridges in the magazine chamber of a gun, said clip comprising stack embracing side portions arranged to 85 impart a lateral pressure on the stack, a projection on each side portion of the clip adapted for engagement by elements of the gun when the clip is inserted therein so as to prevent the contraction of the sides of the clip when any of the cartridges are removed from the stack.

19. A cartridge clip for holding a stack of cartridges in a double row in staggered mutually engaging relation and adapted to be contained with said cartridges in the magazine chamber of a gun, said clip comprising a back and two sides forming a receptacle open at the front, top and bottom, the sides of said clip extending over the sides of the stack and arranged to impart a lateral pressure on the stack, an inward projection at the forward part of each side portion of the clip 100 105 adapted for engagement by elements of the gun when the clip is inserted therein so as to prevent the contraction of the sides of the clip when any of the cartridges are removed from the stack.

In testimony whereof I have affixed my signature.

JOHN D. PEDERSEN.
